STRINGED MUSICAL INSTRUMENT

George D. Beauchamp, Los Angeles, Calif., assignor to Electro String Instrument Corporation, Los Angeles, Calif., a corporation of California

Application January 14, 1936, Serial No. 59,032

7 Claims. (Cl. 84—1)

This invention relates to musical instruments and relates more particularly to electrical musical instruments of the violin type. A general object of this invention is to provide a practical, compact and effective electrical stringed musical instrument.

Stringed musical instruments of various characters have been introduced having electrical pick-up units or electro-magnetic pick-up units for converting the vibrations produced by the strings into modulations in an electrical circuit to be amplified and reproduced as music. It has been the usual practice to include a pick-up of this character in the instrument in addition to its usual or original sounding board or resonant body. The sounding board or resonant body of a violin or a similar instrument is rather large and cumbersome and renders the instrument difficult to handle and play. The embodiment of an electrical pick-up unit in the instrument in addition to its usual sound board or resonant body of course increases the weight and bulk of the instrument.

Another object of this invention is to provide an electrical stringed instrument of the violin type that is extremely light in weight and well balanced, and, therefore very easy to handle and play.

Another object of this invention is to provide an electrical stringed instrument of the violin type that has its center of gravity and its greatest mass immediately adjacent its inner end to be supported on the shoulder of the player and has a simple, very light stub neck devoid of keys and all other parts, which imposes little or no weight on the fingering hand of the player, making the instrument very easy to play.

Another object of this invention is to provide an electrical stringed instrument of the violin type in which the key box portion or peg box portion is at the inner end of the neck to be arranged against the shoulder of the player, as distinguished from the usual form of violin in which the peg box is at the outer end of the neck and must be supported by the fingering hand of the player.

Another object of this invention is to provide an electrical stringed instrument of the violin class that is of novel construction, whereby the shoulder engaging portion or the shoulder pad on such portion comfortably rests on the shoulder of the player and the finger board of the neck is elevated in the proper position for playing.

Another object of this invention is to provide an electrical stringed instrument of the character

mentioned that is very simple in construction and light in weight, comprising a one piece casting or body forming the neck, the key box portion or peg box portion, and the shoulder engaging portion of the instrument.

Another object of this invention is to provide a stringed instrument of the violin type that embodies a novel, simplified and improved electro-magnetic pick-up unit of the general character fully described and claimed in my co-pending application Serial No. 728,717, filed June 2, 1934, which has matured into Patent No. 2,089,171, granted August 10, 1937, for converting the vibrations of the several strings into pulsations or modulations in an amplifying sound reproducing circuit.

Another object of this invention is to provide a stringed musical instrument of the violin type that embodies an electro-magnetic pick-up unit embodying permanent magnets and a coil between the polar parts of the magnets, the magnets and coil being positioned so that the strings pass between the coil and the proper polar parts of the magnets whereby the vibrations of the strings vary the density of the magnetic flux or disturb the magnetic field and thus produce an induced current in the coil, the arms of the magnet being damped to prevent sound producing vibrations of the magnets.

Another object of this invention is to provide an electrical musical instrument of the character mentioned that embodies an electro-magnetic pick-up unit in which the magnets are shaped and the core magnets of the coil are proportioned and located to have the proper substantially uniform spaced relationship to the strings which are arranged in a segmental or arcuate series.

Another object of this invention is to provide a stringed musical instrument of the character mentioned in which the pick-up unit is very compact and light in weight and is arranged so that it does not interfere with the playing of the instrument.

The various objects and features of my invention will be fully understood from the following detailed description of a typical preferred form and application of my invention, throughout which description reference is made to the accompanying drawings, in which:

Fig. 1 is a top or plan view of the instrument provided by the present invention. Fig. 2 is a side elevation of the instrument. Fig. 3 is an enlarged transverse detailed sectional view taken as indicated by line 3—3 on Fig. 1. Fig. 4 is an en-

larged transverse detailed sectional view illustrating one of the string tuning units being a view taken as indicated by line 4—4 on Fig. 2. Fig. 5 is an enlarged transverse detailed sectional view taken as indicated by line 5—5 on Fig. 1. Fig. 6 is a fragmentary longitudinal detailed sectional view taken as indicated by line 6—6 on Fig. 5. Fig. 7 is a fragmentary elevation view of the under side of the key box portion of the instrument showing a part thereof in cross section, being a view taken as indicated by line 7—7 on Fig. 2 and Fig. 8 is a diagrammatic wiring diagram of the circuits involved in the invention.

The improved electrical stringed musical instrument of the present invention includes, generally, a unitary body A having a neck 10, a key box portion or peg box portion 11 and a portion 12 for engaging the shoulder of the player, tensioned strings B extending over the fingerboard 20 of the neck 10 and an electro-magnetic pick-up unit C on the neck 10 for converting vibrations of the strings B into pulsations or modulations in an amplifying circuit.

The construction and shape of the body A and the relation between the several parts of the body A are important features of the invention. The body A is preferably formed of metal, or other material that may be cast in the form of a single, integral part or casting. In practice I have found it desirable to form the body A of a synthetic organic substance resulting from the chemical condensation of phenol and formaldehyde which is relatively light, strong and capable of being attractively finished. In accordance with the invention the body A is an integral one-piece member and provides or forms all of the principal frame parts and supporting parts of the instrument.

The neck 10 over which the strings B are strung is an elongate part comprising the forward or outer portion of the instrument. The neck 10 is shaped to be readily and properly engaged and held by the player's fingering hand. The neck 10 is preferably tapered both horizontally and vertically toward its outer end to be of less cross sectional dimension adjacent its outer end than at its inner end where it joins the portion 11. The lower or under side of the neck 10 is rounded or provided with a convex surface 14. In the preferred construction the neck 10 is tubular or hollow to be light in weight and easy to handle. A longitudinal groove 15 is provided in the neck 10 and has the same general contour as the external surface of the neck. The fingerboard 16 of the neck 10 closes the upper end of the groove 15. The fingerboard 16 may be cemented or otherwise fixed in place. The upper side or surface 17 of the finger board 16 is transversely convex throughout the major portion of its length and is shaped and finished so that the strings B may be properly pressed against it.

The outer end portion 18 of the neck 10 may be slightly enlarged and of ornamental configuration. A curved or concave surface 19 is provided on the under side of the neck 10 adjacent its extreme outer end portion 18 to form a stop or abutment for the hand of the player. The end portion 18 of the neck 10 is shaped and formed to hold the end portions of the strings B as will be hereinafter described. In accordance with the invention a projection 20 is provided on the under side of the neck 10 at a point spaced between its opposite ends. The projection is intended to form a support or abutment engageable by a part of the player's hand as he engages or fingers the

strings B. The projection 20 corresponds, generally, in function, to the button of a typical violin. In practice the projection 20 is preferably integral with the neck 10 and is substantially round in transverse cross section. 5

The invention provides means for locating the playing hand and the string depressing fingers of the player. A member or part 60 projects laterally from the neck 10 at that side of the neck over which the player extends his fingers to depress the strings B. The part 60 preferably projects laterally outwardly from the lower side of the neck 10 at the projection 20, as illustrated in Figs. 1 and 2 of the drawings. In practice the part 60 may be of substantial width and the part is preferably curved or bowed, being curved laterally outwardly and in the direction of the body portion 11. The curved surface 61 thus presented by the part 60 forms an effective rest or means for locating the player's fingers with respect to the strings B and the neck. The invention contemplates the forming of the part 60 integral with the neck 10 or as a separable member attached to the neck 10. In the simple case illustrated in the drawings the part 60 has one end attached 25 to the projection 20 by pins or screws 62 and has an arm or lug 63 on its other end secured to the under side of the neck by a pin or screw 64. Where the part 60 is a separable member it may be formed of sheet stock such as sheet aluminum 30 and the lug 63 may be twisted to properly engage against the neck 10.

A transverse slot or notch 21 is provided in the upper side of the neck 10 to receive or carry the pick-up unit C. The notch 21 is adjacent the 35 inner end of the neck 10 being spaced inwardly a considerable distance from the projection 20. The portion of the neck 10 provided with the opening or notch 21 may be solid or without the groove 15, as illustrated in Fig. 6 of the drawings 40 and may be thickened as at 22.

The key box portion or the peg box portion 11 of the body A integrally joins the inner end of the neck 10 and is provided to carry the keys or pegs 23 for tensioning the strings B. The portion 45 11 of the body A may be substantially rectangular in its general configuration having slightly inwardly converging sides 24. The portion 11 is preferably hollow and provided with an internal space or cavity 25 which may be open at the 50 under side of the portion 11. A central longitudinal web 26 extends through the interior or cavity 25 of the body portion 11 and a transverse bridge or web 27 connects the forward or outer portion of the web 26 with the sides 24. The 55 upper wall 28 of the portion 11 is provided with spaced openings or slots 29 for receiving the strings B. It is a feature of the invention that the body portion 11 just described is angularly related to the neck 10. The key box portion or 60 peg box portion 11 extends downwardly and inwardly from the inner end of the neck 10 as clearly illustrated in Fig. 2 of the drawings. This position or formation of the body portion 11 provides for the proper positioning of the neck 10 65 and the easy fingering of the strings B when the body portion 12 is supported against the shoulder of the player. The above described relationship between the neck 10 and the body portion 11 assures the comfortable engagement of the body 70 portion 12 or the shoulder pad (not shown) on the portion 12 with the shoulder of the player while the neck 10 is properly elevated in playing position. 75

The invention provides improved means for

very accurately tuning the strings B by finely regulating the tension of the strings. Adjusting or regulating units U are provided on the key box portion 11 of the body A for effecting the fine accurate adjustment of the tension on the strings B. Fig. 4 of the drawings illustrates one of these units U in detail. Each unit U includes a plate 70 attached to the upper face of the body portion 11 by screws 71 or the like. The plates 70 of the units U are disposed below and transversely of the strings B. A block 72 is arranged on one end part of each block 70 and screws 73 secure the blocks 72 to the plates 70. The screws 73 project from the upper sides of the blocks 72 and are provided with heads 74. The units U include tilttable or pivotable plates 75 arranged on the blocks 72. The screws 73 freely pass through openings 76 in the plates 75 to pivotally support or retain the plates 75. The heads 74 of the screws 73 limit the pivotal movement of the plates 75 and prevent the displacement of the plates. Each plate 75 carries means for engaging or bearing on a string B. In the simple form of the invention illustrated a slotted screw 77 projects from the upper side of each plate 75 and the string B passes through its slot as clearly illustrated in Fig. 4 of the drawings. An adjusting screw 78 is threaded through an opening in each plate 75 and its inner end is adapted to engage or bear against the fixed plate 70. In practice the ends of the adjusting screws 78 may be suitably rounded and may cooperate with correspondingly shaped recesses 79 in the plates 70. Knurled heads 80 may be provided on the adjusting screws 78 to facilitate the accurate manual adjustment of the screws. Means is provided for preventing swinging or turning of the plates 75. Pins 81 project from the plates 75 and extend into openings 82 preventing undesirable lateral swinging of the adjustable plates 75. The plates 75 are positioned or set to exert an upward force on the strings B or to form bridges on which the strings bear. The screws 78 may be threaded or turned to react against the fixed plates 70 and thus pivot or adjust the bridge plates 75. By carefully turning or adjusting the screws 78 the tension on the vibratory strings B may be very accurately regulated as desired. The units U are very compact and are light in weight.

The portion 12 is provided on the inner end of the body A for engaging the shoulder and chin of the player or for carrying a suitable shoulder pad (not shown) for engaging the shoulder or for carrying a chin rest (not shown) for cooperating with the chin of the player. The shoulder engaging portion 12 of the body A projects laterally in one direction from the inner end of the portion A. The rear or inner side 30 of the portion 12 is curved forwardly to join its forward face. The upper and lower faces of the portion 12 may be substantially horizontal or substantially parallel with the plane of the longitudinal axis of the neck 10. In accordance with the invention the portion 12 is preferably hollow having an internal cavity 31. The upper side of the cavity 31 is closed by an integral wall 32 of the body A while the lower side of the cavity 31 is closed by a plate 33 cemented or otherwise fixed in position.

The strings B are strung across the finger board 16 of the neck 10 between the outer end portion 18 of the neck and the body portion 11. In accordance with the usual practice there are four strings B of graduated diameters. The 75 strings B are formed of steel or other magnetic

material to influence the pick-up unit C. Spaced openings 35 are provided in the outer end portion of the body neck 10 to receive the end portions of the strings B. Suitable nuts, spools or the like are provided on the strings B to cooperate with the openings 35 to hold the strings against movement in one direction. The strings B pass over a bridge 36 at the outer end of the finger board 16. A bridge 37 is provided at the inner end of the finger board 16 and the strings B 10 extend inwardly over the bridge 37 to be in the proper spaced relation to the finger board 16. The bridge 36 is preferably integral with the one piece body A while the bridge 37 may be inserted in and secured in a notch 38. It is to be understood that bridges of various characters may be employed on the instrument if desired. The upper or active string supporting edges of the bridges 36 and 37 are arcuate and support the strings B in spaced relation in a curved or arcuate series to be in their proper relation to the surface 17 of the finger board 16. The usual notches may be provided in the bridges 36 and 37 to maintain the strings B in their proper positions. The strings B extend inwardly from 25 the bridge 37 to pass through the slots 29 into the cavity 25 of the body portion 11. The end portions of the strings B are wound on the keys or pegs 23 whereby the strings may be tightened and tuned by means of the pegs 23.

The pick-up unit C is operable to convert the actual tone producing vibrations of the strings B into pulsations or modulations in an amplifying circuit 40. The pick-up unit C is such that the intensity, frequency, etc. of the sound producing vibrations of the strings B act through the medium of a magnetic field to modulate the amplifying circuit 40 in a proportional or definite manner so that the amplifying circuit 40 is influenced to faithfully and accurately reproduce the sound. In accordance with the invention the pick-up unit C includes a magnet or a magnet assembly comprising a pair of like opposed magnets 41. It is a feature of the present invention that the magnets 41 are permanent magnets as distinguished from electro-magnets which might influence the amplifying circuit 40 to produce a hum or other undesirable sound. The magnets 41 are substantially U-shaped in their general configuration, each having two spaced arms 42 and 43. The magnets 41 are arranged in the opening or notch 21 so that their lower arms 42 rest or bear on the inner wall of the notch. In the preferred construction the magnets 41 are proportioned to project from the opposite sides of the neck 10 to be of sufficient length to insure the proper operation of the unit C. In accordance with the invention the magnets 41 are arranged in opposed relation, that is, the confronting or opposed ends of their arms 42 and 43 have opposite polarity as indicated in Fig. 5 of the drawings. This provides a continuous state of polarity at the opposite sides of the assembly of magnets. It is preferred that the confronting or opposed ends of the arms 42 and 43 of the magnets 41 be in spaced relation.

The upper or outer arms 43 of the magnets 41 are formed or shaped to have the proper relationship to the arcuate series of vibratory strings B. The inner end portions 43a of the magnet 70 arms 43 are curved upwardly and inwardly to extend over the arcuate series of strings B and be substantially equally spaced from the strings. The several strings BB thus influence or affect the proper zone of the magnetic field of the magnet 75

assembly 41—41. The invention provides a simple and particularly effective means for securing the pick-up unit C to the body A and for dampening the magnets 41 to prevent vibration of their arms. Screws 44 are passed through openings 45 in the neck 10 and extend through openings 46 in the lower arms 42 of the magnets 41. The upper ends of the screws 44 engage or bear against the under sides of the inner portions 43a of the magnet arms 43. This engagement of the screws 44 with the arms 43 prevents vibratory movement of the arms which might produce a ringing sound. The screws 44 are preferably of non-magnetic material so that they do not short out or affect the magnets 41.

The magnets 41 arranged or mounted as just described have the portions 43a or their upper arms 43 passing over or above the strings B in spaced relation to the strings. Thus the strings 20 B pass through the lines of force of the magnetic field and when vibrated vary the density of the magnetic flux. The magnets 41 may be carefully adjusted or set when assembled on the body A to be in the proper relation to the strings B. The 25 pick-up unit C provides or includes a coil 48 arranged within the magnet assembly 41—41. The coil 48 is arranged on the inner or lower arms 42 of the magnets 41 and operates to pick up or receive an electrical current from the field of the 30 magnet assembly. The coil 48 is wound on a coil form or spool 49 of the proper configuration. The coil 48 constitutes a winding of suitable enameled wire of the proper gauge trained or wound on the spool 49 between its end flanges. The spool 49 is 35 preferably formed of a suitable non-magnetic insulating material and has openings 49a receiving the screws 44 whereby the screws operate to hold the coil in place. It will be understood that the number of turns on the coil 48 and the gauge of 40 the wire forming the coil depend upon the particular amplifying circuit 40 with which the instrument is to be used. The coil C positioned within the assembly of the magnets 41 is located between the north and south poles of the magnet 45 assembly and is related to the strings B to be affected by their vibration. The upper side of the coil spool 49 is spaced some distance below the arcuate series of strings B and disturbances in the magnetic field or flux of the magnets 41 resulting 50 from vibration of the strings B induces an electric current in the coil 48.

The pick-up unit C includes a plurality of core members 50 for attracting the lines of magnetic force toward the center of the coil 48. The members 50 are in the nature of pins or posts projecting from the upper side of the coil spool 49. The lower ends of the members 50 preferably engage the lower arms 42 of the magnets 41. In 60 accordance with the invention the upper ends of the members 50 are spaced below or inwardly from the strings B there being one member 50 spaced from each string B. The post members 50 of the coil project different distances from the spool 49 so that the spaces between their upper 65 ends and the strings B are graduated substantially in proportion to the graduation in diameter of the strings. This spacing or relationship between the upper ends of the coil members 50 and the strings B operates to compensate for differences in 70 the degree of variation of the magnetic reluctance or variation in the magnetic reluctance when the strings are vibrated due to the differences in the diameter of the strings.

One lead or conductor 51 from the amplifying 75. circuit 40 extends through a suitable opening in

the neck 10 and is electrically connected with the outer winding of the coil 48. The other lead or conductor 52 extending to the amplifying circuit 40 is electrically connected with one of the magnets 41. A post or member 50 bearing on the 5 lower arm 42 of this magnet engages the inner windings of the coil 48 to complete the circuit through the coil. The enamel on the inner windings of the coil 48 is removed where they engage the said member 50. The posts or members 50 10 operate to carry the stronger lines of the magnetic force into the center of the field of the coil 48. The strings B pass between the ends of the members 50 and the magnet arms 43 vary the density of or disturb the lines of force of the magnetic assembly and thus set up or induce an electrical circuit in the coil 48 picked up from the magnetic field.

The coil 48 of the pick-up unit C is electrically connected to the amplifying circuit 40 which 20 may also be a speaker or sound reproducing unit. Thus variations in the density of the magnetic flux picked up by the field of the coil 48 are converted into sound. This sound reproduced by the amplifying and sound reproducing circuit 40 25 is a true reproduction of the sounds or tones produced by the vibratory strings B. It is to be understood that any suitable form of amplifying and sound reproducing device or unit may be employed in connection with the pick-up unit C and that the typical unit 40 illustrated in the drawings 30 is not to be construed as limiting the scope or application of the invention.

The invention includes means for conveniently associating or connecting the coil 48 of the unit C 35 on the portable musical instrument with an amplifying and sound reproducing unit such as the circuit 40. In the preferred structure illustrated in the drawings a socket or jack 53 is arranged in an opening in the forward wall of the inner portion 12 of the body A. The jack 53 projects into the cavity 31 of the body portion 12. The jack 53 is adapted to receive a plug 54 connected with the leads or conductors 55 from the amplifying circuit 40. The conductors 51 and 52 extend through the opening or cavity 25 of the body portion 11 and pass through an opening 56 in the body to extend into the cavity 31. The invention includes means for varying the amplification of the sound. A volume control is provided on the instrument or 40 violin in a position to be conveniently accessible to the artist or player. The lines or conductors 51 and 52 extend through the cavity 31 to the jack 53, and the amplifying control or volume control 45 may be in the form of a variable resistance element or rheostat 58 arranged in the cavity 31 and interposed or connected in the conductors 51 and 52. The control handle or knob 59 of the volume control or rheostat 58 projects from the curved 50 inner surface 30 of the body portion 12 where it is 55 conveniently accessible to the artist or player.

In playing the instrument the body A is held or positioned with the portion 12 resting or bearing against the shoulder and with the neck 10 engaged by the finger hand of the player. It is to be 60 understood, of course, that the portion 12 of the instrument body A may be provided with the proper shoulder pad (not shown) and chin rest (not shown). As the center of greatest mass and the center of gravity of the instrument is adjacent 65 its inner end the instrument is readily supported or held in this manner. It is to be particularly noted that the neck 10 is very light in weight and does not carry or support any heavy or cumbersome parts. The neck 10 terminates at its outer 70 75.

end in the portion 18 which merely carries the dead or fixed ends of the strings B. This stub neck 10 is tubular or hollow and when the instrument is in the proper playing position imposes little or no weight on the artist's hand which fingers the strings B. The arranging or locating of the keys or pegs 23 in the portion 11 of the body A removes the weight of the pegs and the necessary relatively heavy body portions for carrying the keys from the outer end of the neck which is the position they usually occupy in a typical violin.

A typical bow is drawn over the strings B between the unit C and the bridge 37 or at any other point adjacent the unit C to cause vibration of the strings. Vibration of the strings by the bow or by plucking results in variations or disturbances in the magnetic field to induce a current in the coil 48. The current of the coil 48 is amplified by the circuit 40 and converted into a reproduction of the sound of the instrument by the circuit 40 and its associated parts. It will be obvious that the vibratory strings B influencing or disturbing the magnetic flux adjacent or above the post members 50 of the coil 48 induces a current in the coil 48 having the frequencies and other characteristics of the vibrations of the strings to accurately or proportionately influence the circuit 40. The amplifying and sound reproducing circuit 40 receiving these pulsations or modulations faithfully produces the sound produced by the strings B, which sound has all the tonal qualities of the sound of the strings. The volume of the sound produced or reproduced by the circuit 40 may be easily and conveniently controlled by the artist or player by turning the knob 49. It is to be noted that the electrical musical instrument of the present invention operates to amplify the true tones produced by the vibratory strings without vibration of any other physical parts of the instrument proper.

The instrument or violin comprising the single one-piece body A formed of light material and provided with the openings and cavities described above is extremely light and is very compact. The instrument does not involve any sounding parts or resonant boxes. The neck 10 and the portions 11 and 12 of the body are proportioned and related so that the instrument may be easily and conveniently handled by the player or artist and the relationship of the parts is such that the neck 10 and fingerboard 16 are properly positioned for playing when the body portion 12 is supported on the shoulder.

Having described only a typical preferred form and application of my invention, I do not wish to be limited or restricted to the specific details herein set forth, but wish to reserve to myself any variations or modifications that may appear to those skilled in the art or fall within the scope of the following claims:

Having described my invention, I claim:

1. In an electrical stringed instrument a neck having a finger board, a plurality of spaced tensioned vibratory strings extending over the finger board in spaced relation thereto, a magnet on the neck having its poles at opposite sides of the strings, the magnet comprising spaced arms, a coil between the poles of the magnet positioned so that the strings pass between it and the adjacent arms of the magnet, the coil being operable to convert the flux of the magnet into a current which is modulated by vibration of the strings, and means for dampening the arms of the magnet to prevent vibration thereof.

2. In an electrical stringed instrument a neck

having a finger board, a plurality of spaced tensioned vibratory strings extending over the finger board in spaced relation thereto, a magnet on the neck having its poles at opposite sides of the strings, the magnet comprising spaced arms, a coil between the poles of the magnet positioned so that the strings pass between it and the adjacent arms of the magnet, the coil being operable to convert the flux of the magnet into a current which is modulated by vibration of the strings, and means for dampening the arms of the magnet to prevent vibration thereof, said means including securing members engaging said arms and securing the magnet and coil to the neck.

3. In an electrical stringed instrument a neck having a finger board, a plurality of spaced tensioned vibratory strings extending over the finger board in spaced relation thereto and arranged in an arcuate series, a magnet on the neck having its poles at opposite sides of the strings, the magnet comprising inner arms and outer arms, the outer arms being arcuately curved to follow generally the curvature of the series of strings, and a coil between the poles of the magnet positioned so that the strings pass between it and the adjacent arms, the coil being operable to convert the flux of the magnet into a current which is pulsated by vibration of the strings.

4. In an electrical stringed instrument a neck having a convex fingerboard, a plurality of spaced tensioned vibratory strings extending over the fingerboard in spaced relation thereto and arranged in an arcuate series, a magnet on the neck having its poles at opposite sides of the strings, the magnet comprising inner arms and outer arms, the outer arms being arcuately curved to follow generally the curvature of the series of strings, a coil between the poles of the magnet positioned so that the strings pass between it and the adjacent arms, and core members projecting from the coil toward the strings, the spacing of the members from the adjacent strings being substantially uniform.

5. In a stringed musical instrument having a body and a plurality of spaced tensioned strings extending across the body in spaced relation thereto, a pick-up unit comprising a pair of opposing magnets on the body, each magnet having an arm above the strings and an arm below the strings, an induction coil in the field of the magnets operable to convert the flux of the magnets into a current that is modulated by vibration of the strings, and screws passing through openings in the body, the lower arms of the magnets and the coil to secure the magnets and coil to the body and engaging the upper arms of the magnets to prevent vibration of the same.

6. In a stringed musical instrument having a body and a plurality of spaced tensioned strings extending across the body in spaced relation thereto, the strings being graduated in diameter and being arranged in an arcuate series, a pick-up unit on the body comprising a pair of magnets each having an arm spaced below the series of strings and an arm spaced above the series of strings, the last mentioned arms being curved to follow generally the curvature of the arcuate series of strings, an induction coil between the upper and lower arms of the magnet positioned so that the strings pass between it and the upper magnet arms, and core members projecting from the coil toward the upper magnet arms and each having an upper end spaced from a string, the spaces between the upper ends of the core mem-

bers and the adjacent strings being substantially uniform but graduated substantially in proportion to the graduation in diameter of the strings to compensate for differences in the extent of variation of the magnetic flux by vibration of the graduated strings.

7. In a stringed musical instrument having a body and a plurality of spaced tensioned strings extending across the body in spaced relation thereto the strings being arranged in an arcuate series, a pick-up unit on the body comprising a pair of opposed U-shaped permanent magnets each having an arm spaced below the series of strings and an arm spaced above the series of

strings, the magnet arms projecting laterally beyond the opposite sides of the series of strings, the upper arms of the magnets having substantially straight outer portions and having inner portions curved to substantially conform to the curvature of the arcuate series of strings, an induction coil in the field of the magnets, and core members projecting from the coil toward the strings whereby the vibratory strings pass through fields in which the lines of magnetic force converge toward the outer ends of the core members.

GEORGE D. BEAUCHAMP.
